UNITED STATES PATENT OFFICE.

JAMES I. AYER, OF CAMBRIDGE, MASSACHUSETTS, ASSIGNOR TO SIMPLEX ELECTRIC HEATING COMPANY, OF BOSTON, MASSACHUSETTS, A CORPORATION OF MASSACHUSETTS.

CONDITION-CONTROLLING DEVICE.

No. 904,917.

Specification of Letters Patent.

Patented Nov. 24, 1908.

Application filed October 29, 1906. Serial No. 340,948.

To all whom it may concern:

Be it known that I, JAMES I. AYER, a citizen of the United States, residing at Cambridge, in the county of Middlesex and State 5 of Massachusetts, have invented an Improvement in Condition-Controlling Devices, of which the following description, in connection with the accompanying drawing, is a specification, like letters on the drawing representing like parts.

The present invention relates to a device for automatically controlling the condition of another device. In the specific embodiment of the invention illustrated herein it 15 appears as a temperature controlling thermostat, such as may be employed for example in maintaining an oven at a given desired temperature. It will be seen, however, that the principles involved in the invention 20 are by no means limited to the controlling of a temperature condition, but may be applied equally to the controlling of pressure, volume, or other condition.

The condition controlling device of this 25 invention is essentially an electrical device and embodies among others the novel features of means for adjusting the state of condition to be maintained, means for producing accuracy by a device for multiplying 30 the movement of the element controlled by the change of condition, and means whereby the electrical contact points of the device secure their effective action without impeding in any way the movement of the element indicating the change of condition.

The exact nature of the invention can best 35 be seen from the accompanying specification and drawings describing and illustrating a temperature controlling thermostat embodying the invention in a preferred and specific form, and the extent of the invention will be defined by the accompanying claims.

The drawings represent a temperature controlling thermostat, together with a diagrammatic illustration of suitable electric 45 circuits.

In the drawings, Figure 1 is a vertical side elevation, partially in cross-section, of the entire thermostat: Fig. 2 is a vertical front 50 elevation of the device: Fig. 3 is a horizontal sectional view taken on the lines $x-x$, Figs. 1 and 2: Fig. 4 is a diagrammatic view of the thermostat, and electrical means

for operating the supply of heat, and suitable electric circuits for the same.

In the specific embodiment of the invention herein illustrated as a temperature controlling thermostat, A is a rigid framework offset at the lower end to present a lug a, 60 and forked at the upper end to present two arms b, b forming a yoke.

The yoke b, b supports two rods b', b², both of which serve as guides and supports for the contact point frame b³, movable 65 thereon. The rod b² is provided with a thumb-nut b⁴, stops b⁵, b⁶ abutting against the arms b, b and preventing longitudinal movement of the rod, and a lock nut b⁷, and has a screw-thread engagement with the contact point frame b³, whereby upon the rotation of the thumb-nut b⁴ the contact point frame b³ may be adjusted transversely of the frame and locked in position.

The contact point frame carries pivoted 75 thereto as at c, c, and insulated therefrom and from each other, two electric contact points c', c', which are held in their lowermost position by stops c², and which when pressed upon by a movable element coming 80 into contact with either of the beveled sides of their lower ends yield and swing upwardly, allowing the element to pass by. Binding posts c³ at the rear of the contact point frame b³ are in electrical connection 85 one with each contact point c', and serve for the attachment thereto of the wires of an electric circuit or circuits.

In the device illustrated it is designed that the movable element which is controlled by 90 the condition of the device, such for example as the temperature of an oven, shall upon opposite changes of the said condition, such for example as the rise or fall of the temperature, come into contact with the proper 95 one of the electric contact points c', and thereupon complete an electric circuit which, through intervening devices, shall act to restore the normal or desired condition.

In the device illustrated the movable element is an ordinary laminated long, thin flat bar D, fastened at its lower end to the lug a and bending at its upper end in opposite directions, accordingly as the temperature to be controlled rises or falls.

If the laminated arm D be placed in direct engagement at its upper end with the con-

tact points c' , c' , it would be difficult, if not impractical, to obtain any very close adjustment of the condition or temperature, because if the laminated arm be made of sufficient length to have an appreciable movement at its upper end for a slight change in temperature, it would be found so delicate as to be easily affected by any local vibration to which it might be subjected, and unless it should be kept in a perfectly still position it would not be capable of close adjustment. For this reason an auxiliary element, herein termed a multiplier, has been introduced between the free end of the laminated arm or operating element and the contact points. This permits the use of a comparatively short and stocky laminated arm, which is not easily affected by any jarring or vibration, and yet secures a close adjustment.

20 The multiplier is shown as a lever pivoted at f on the contact point frame b^2 , and made up of two pieces e , e' , insulated from each other, the former of which carries a pin e^2 , coöperating with a longitudinal slot b in the cross-head d' of the laminated arm D , and the latter of which is flattened at its upper end to vibrate between the contact points c' , c' and come into engagement therewith.

An electrical connection with one branch 30 of the electric circuit is made with the upper part e' of the lever or multiplier in any suitable manner. Herein the wire coil f extends from the part e' to a pin f^2 , in connection with a binding post f^3 attached to but 35 insulated from the contact point frame b^2 .

The cross-head d' carries a flat spring d^2 , adjacent its upper surface, so that when the pin e^2 rides out of the slot in the cross-head the said spring will hold the pin and prevent 40 the lever e , e' from turning up side down, and also serves to guide the pin e^2 back into the slot d upon the return of the parts toward alined position.

The delicacy of the adjustment will depend, of course, upon the relative proportion 45 of the parts, and especially upon the position of the pivot of the lever e , e' . With the arrangement shown the movement of the laminated arm is multiplied about four times.

50 The general operation of the device illustrated may be best understood by reference to the diagrammatic illustration of Fig. 4, where H represents the device, the condition of which is to be controlled. The condition 55 herein illustrated is one of temperature, and the temperature is herein shown as dependent upon a resistance, part of which is shown at h , in an electric circuit, the main wires 1, 2 of which extend to a suitable source of electric energy, not shown.

The supply of current to the resistance h is shown as directly controlled by a switch-arm h' operated by two magnets M , M' , the construction and operation of which need 60 not herein be described, but is fully set forth

in Patent No. 773,182, granted to me on October 25, 1904, for automatic electric switches. The contact points c' , c' , through the binding posts c^3 , c^3 are connected by the circuit wires 3 and 4, one with each magnet 70 M , M' , while the contact arm e' of the multiplier lever is connected by the circuit wire 5 with the main line wire 1. It will thus be seen that when it is desired to maintain the device H at a given temperature the thumb screw b^7 is turned to adjust the contact point frame b^2 and the parts carried thereby to such position that the contact arm e' of the multiplier lever shall be centrally between the contacts c' , c' when the laminated arm D 80 is in the position resulting from the desired temperature of the device H . In this position current is supplied to the resistance h , and the switch-arm h' is in engagement with the lower contact completing the circuit 85 through the resistance.

If the temperature rises above the desired point the laminated arm H will move in one or the other direction, according to its construction, as for example to the left, throwing the multiplier into engagement with the contact point c' , connected to the wire 3, thereupon energizing the magnet M' and cutting out the resistance h , whereupon the temperature will begin to fall, and then the laminated arm H will swing in the opposite direction toward the right, bringing the multiplier into engagement with the contact point in connection with the wire 4, thus energizing the magnet M and throwing in 100 the resistance h . In this manner the temperature of the device H will be kept substantially constant at the desired degree.

It is important that the contact points with which the laminated arm or multiplier come into engagement shall be so arranged that they do not impede the movement or action of the laminated arm, and yet that they shall be effective in producing prompt action with a slight movement of the thermostat. It is necessary that the moving element engaging with the contact points shall pass freely from one extreme position to another as it may be moved by the changes in condition or temperature at whatever point of adjustment the apparatus may be set, without affecting the sensitiveness of the device or the closeness of the adjustment or regulation to the desired temperature. In 110 the device illustrated herein, for example, when the device H heats up the laminated arm will come over and cause the multiplier to press against the contact points, and to continue its movement after making contact, notwithstanding the heat supplied is immediately cut off or reduced at the moment of contact, because with almost any arrangement or source of heat the stored energy in the heater, when electric or other heater is used, will continue to give out heat and 120 130

cause the temperature to continue to rise, and thereby force the laminated arm or multiplier onward, increasing its pressure against the contact point. Now, if the contact point be fixed the laminated arm is liable to be bent, consequently changing the adjustment of the temperature. If the contact points are adjusted after the device has reached its desired temperature, and these points limit the travel of the laminated arm or multiplier when the current is cut off, unless the contact points are removed the laminated arm will be prevented from returning to its normal position, which it takes at low temperature. By making the contact points movable to allow of the free passage of the laminated arm or multiplier after it comes into contact these difficulties are avoided. The contact points when pivoted as shown are always in proper position and are readily moved out of the way by the laminated arm itself when, as is usual, a movement greater than necessary to make contact takes place.

25 A continued engagement between the pin c^2 of the multiplier and the slot d of the cross-head on the laminated arm throughout extended ranges of movement of the laminated arm would produce binding of the parts and require a long slot. By the construction illustrated the pin c^2 remains in the slot for a limited range of movement, but when the movement increases the pin leaves the slot and rides along on the top of the cross-head and beneath the spring d^2 , preventing the multiplier arm from assuming a horizontal position or turning completely over. When the parts return to position where a contact is to be made the pin 40 will return into the slot under the guiding influence of the spring.

While in the specific embodiment of the invention illustrated an electric heater has been shown, it is obvious that the thermostat may be applied to any other heater, and while in the said device electro-magnets are shown for controlling the heat, yet it is obvious also that any other motor or actuating device for performing the functions necessary may be employed. The invention in fact is applicable to various devices wherein a change of various conditions, such as heat, pressure or volume, is to be controlled. It is only necessary that there should be a movable arm or member operating upon a change in condition, the movement of which may be utilized in connection with the electric contacts of the device. The invention presents a device of such a nature as to be made very accurate and sensitive, and which has a range of adjustment between wide limits without interfering with the accuracy of its performance at any given point for which it may be set, and which in the event of the 65 operation being discontinued, such for ex-

ample as cutting off the heat supply entirely when applied to the control of heat or temperature does not in any way need attention to insure its working as before whenever the source of energy is again supplied. 70

Having described my invention, what I claim as new and desire to secure by Letters Patent, is:

1. A condition controlling device comprising a support, a pair of contacts pivotally mounted therein, a circuit closing element movable to engage either contact according to variations in the conditions to be controlled, said contacts being arranged to yield to a continued movement of said circuit closing member, and means for limiting the pivotal movement of said contacts in the opposite direction. 75

2. A condition controlling device comprising a support, a pair of contacts mounted in said support, provided with overlapping ends, said ends being separated from each other, and a circuit closing element movable to engage either of said overlapping ends according to variations in the conditions to be controlled, said contacts being arranged to yield to a continued movement of said circuit closing member. 85

3. A condition controlling device comprising a support, a pair of contacts pivotally mounted therein and beveled at their effective ends, a circuit closing element movable to engage either contact according to variations in the conditions to be controlled, said contacts being arranged to yield to a continued movement of said circuit closing member, and stops for limiting the movement of each member in the opposite direction. 95

4. A condition controlling device comprising a support, a pair of contacts pivotally mounted therein, said support being provided with stops to limit the pivotal movement of said contacts, and a circuit closing element movable to engage either contact according to the variations in the conditions to be controlled, said contacts being arranged to yield to a continued movement of said circuit closing element. 105

5. A condition controlling device comprising a support, a pair of contacts mounted in said support, provided with overlapping ends, said ends being separated from each other, and a circuit closing element movable to engage either of said overlapping ends according to variations in the conditions to be controlled, said contacts being arranged to yield to a continued movement of said circuit closing member, and means for limiting the movement of each contact in the opposite direction. 115

6. A condition controlling device comprising a support, a pair of contacts carried thereby and each arranged to control an independent circuit, an operating element movable in directions corresponding to varia- 130

tions in the conditions to be controlled, a circuit closing element, means for connecting said elements, and means for maintaining the operative relation of said elements under excessive movement of the operating element.

7. A condition controlling device comprising a support, a pair of contacts pivotally mounted therein, and each arranged to control an independent circuit, an element movable in directions corresponding to variations in the conditions to be controlled, and a circuit closing element operated by the first mentioned element and arranged to move in reverse directions thereto to engage either contact, said contacts being so mounted as to yield to a continued movement of the circuit closing member, means for returning each contact to its normal position thereafter, means for limiting the pivotal movement of said contacts in the opposite direction.

8. A condition controlling device comprising a support, a pair of contacts pivotally mounted therein, and each arranged to control an independent circuit, a thermostat member movable in directions corresponding to the conditions to be controlled, a multiplying lever having its longer arm arranged to engage either contact, said contacts being so mounted as to yield to a continued movement of said multiplying lever and in the direction of movement thereof, means for returning each contact to normal position thereafter, and means for connecting the short arm of said multiplying lever to the free end of said thermostat member, the point of connection between said lever and said member being automatically shiftable during the operation of the parts.

9. A condition controlling device comprising a support, a pair of contacts supported thereby, and each arranged to control an independent circuit, a thermostat member movable in directions corresponding to the conditions to be controlled, a multiplying lever having a pin and slot connection between its shorter arm and the free end of said thermostat member, and the longer arm arranged to engage either contact, said contacts being so arranged as to yield to a continued movement of said multiplying lever and in the direction of movement thereof, and means on either side of said slot for guiding said pin.

10. A condition controlling device comprising a support, a pair of contacts supported thereby, and each arranged to control an independent circuit, a thermostat member movable in directions corresponding to the conditions to be controlled, a cross head on the free end of said thermostat member and provided with a centrally disposed open longitudinal slot, a confining spring mounted upon and extending across the top of the cross head, a multiplying lever having its shorter arm provided with a pin coöperating with said slot and controlling said spring when

out of engagement with said slot, the longer arm of said lever being arranged to engage either contact, said contacts being arranged to yield to a continued movement of said multiplying lever.

11. A temperature controlling device comprising a support, a thermostat member mounted therein, a carrier also mounted therein, means for adjusting said carrier in a direction parallel with the line of movement of said thermostat, a pair of contacts mounted on said carrier, a multiplying lever mounted on said carrier and having one arm in engagement with said thermostat member, the other arm being normally between said contacts and arranged to engage either of them, said contacts being constructed to yield to a continued movement of said lever.

12. A temperature controlling device comprising a support, a thermostat member mounted therein, a carrier also mounted therein, means for adjusting said carrier in a direction parallel with the line of movement of said thermostat, a pair of contacts mounted on said support, a multiplying lever mounted on said carrier and having one arm in engagement with said thermostat member, the other arm being normally between said contacts, and arranged to engage either of them, said contacts being each supported by a pivot, whereby it will yield to a continued movement of said lever, and means for returning each contact to its normal position after the passage of said arm.

13. An adjustable temperature controlling device comprising a frame, a thermostatic arm mounted at the lower end of said frame, a support movable on and transversely adjustable of said frame at its upper end, a pair of contacts pivotally mounted upon said support, a multiplying lever pivoted upon said support and having its shorter arm in loose engagement with the free end of the thermostatic arm, and the end of its longer arm normally between the said contacts, and means for returning each pivoted contact to normal position after the passage of said arm.

14. A condition controlling device comprising a support, a pair of contacts pivotally mounted therein, a circuit closing element movable to engage either contact according to variations in the conditions to be controlled, said contacts being arranged to yield to a continued movement of said circuit closing member, means for limiting the pivotal movement of said contacts in the opposite direction, circuits controlled by said contacts, and means controlled by said circuits for varying the conditions to be controlled.

15. A condition controlling device comprising a support, a pair of contacts carried thereby and each arranged to control an independent circuit, an operating element movable in directions corresponding to variations

in the conditions to be controlled, a circuit closing element, means for connecting said elements, means for maintaining the operative relation of said elements under excessive movement of the operating element, circuits controlled by said contacts, and means controlled by said circuits for varying the conditions to be controlled.

In testimony whereof, I have signed my name to this specification; in the presence of 16 two subscribing witnesses.
